UNITED STATES PATENT OFFICE.

HENRY CAVE AND CHAUNCEY P. MANNING, OF HARTFORD, CONNECTICUT, ASSIGNORS
TO THE FULLER BRUSH COMPANY, OF HARTFORD, CONNECTICUT, A CORPORATION
OF CONNECTICUT.

BRUSH HANDLE.

Application filed October 8, 1923. Serial No. 667,206.

To all whom it may concern:

Be it known that we, HENRY CAVE and CHAUNCEY P. MANNING, each a citizen of the United States, and a resident of Hartford, in the county of Hartford and State of Connecticut, have invented new and Improved Brush Handles, of which the following is a specification.

Our invention relates to devices above named, and an object of our invention, among others, is to provide simple and inexpensive means for securing a handle to the stem of a brush in such manner that the handle will be securely and rigidly held against movement on the stem.

One form of device embodying our invention and in the construction and use of which the objects herein set out, as well as others, may be attained, is illustrated in the accompanying drawings, in which—

Figure 1 is a view in central lengthwise section through a handle shown as secured to the stem of a brush in accordance with our invention.

Figure 2 is an end view of the structure looking toward the outer end of the handle.

Figure 3 is a view in cross section on a plane denoted by the dotted line 3—3 of Figure 1.

In the accompanying drawings the numeral 5 denotes a portion of a brush having the brush material secured to a core 6 by a twisting operation imparted to the wires comprising said core, this being a common way of forming brush structures. The twisted core 6 is intended to form a shank or stem 7 to which the handle 8 is secured.

In adapting our invention to this structure one of the strands 9 of the stem is cut off at a distance from the outer end of the stem to locate the cut-off portion within the handle 8, and the end of the strand 9 thus forms a lug or key 11, as shown in Figure 1 of the drawings. The other strand 10 of the stem is maintained of a length to extend beyond the outer end of the handle 8, and this projecting end is bent into the form of a loop 12, the extreme end 13 of the back-turned portion being projected into a socket 14 in the end of the handle.

In assembling the structure the stem is driven into a hole formed through the handle, the inner portion 15 of this hole

being of a size to quite closely fit the stem 10 and the outer portion 16 of the hole being of a size to quite closely fit that part of the strand 10 projecting beyond the end of the other strand 9. A key-way 17 opens out of the hole 15, and this key-way may be formed, if desired, in the operation of forcing the stem of the brush through the handle, the lug or key 11, in such operation, cutting its way along the wall of the hole 15 and thus forming the key-way 17.

When the stem has been forced into the handle to a sufficient degree so that the outer end of the strand 10 projects to a proper distance beyond the end of the handle, said projecting end is then bent to form the loop 12, in which bending operation the end 13 is forced backwardly into the socket 14.

It will be seen that by the use of our invention a simple and effective way for securing the handle to the stem of the brush is obtained and in such a structure the stem 75 will be held from turning movement by means of the key or lug 7 acting in connection with the end 13 in the socket 14. The handle will also be secured against lengthwise movement on the stem and a loop, by 80 means of which the brush may be suspended from a hook or nail, is obtained as a result of the construction.

In accordance with the provisions of the patent statutes we have described the principles of operation of our invention, together with the device which we now consider to represent the best embodiment thereof; but we desire to have it understood that the device shown is only illustrative and that the 90 invention may be carried out by such other means as fall within the scope of the following claim.

We claim:—

A brush structure including a brush having a stem formed of twisted strands of wire, and a handle into which said stem projects, one of said strands terminating within the handle and having its end projected laterally to form a key located in a key-way extending longitudinally of the handle and opening out of the hole for the stem in said handle.

HENRY CAVE.
CHAUNCEY P. MANNING.
